United States Patent Office

Des. 225,006
Patented Oct. 31, 1972

225,006

BLOCK

George B. Muse, Hillcrest Drive, Calhoun, Ga. 30701

Filed Mar. 8, 1971, Ser. No. 122,258

Term of patent 14 years

Int. Cl. D25—01

U.S. Cl. D18—2

FIG. 1

FIG. 2

FIG. 3

FIG. 4

FIG. 5

FIG. 6

FIG. 7

FIG. 8

FIG. 9

FIG. 10

FIG. 11

FIG. 12

FIG. 1 is a perspective view of a block embodying one form of the design;

FIG. 2 is a bottom plan view thereof;

FIG. 3 is a left end elevational view thereof;

FIG. 4 is a right end elevational view thereof;

FIG. 5 is a perspective view of a block embodying a modified form of the design;

FIG. 6 is a bottom plan view thereof;

FIG. 7 is a left end elevational view thereof;

FIG. 8 is a right end elevational view thereof;

FIG. 9 is a perspective view of a block embodying another modified form of the design;

FIG. 10 is a bottom plan view thereof;

FIG. 11 is a left end elevational view thereof; and FIG. 12 is a right end elevational view thereof.

I claim:

The ornamental design for a block, substantially as shown and described.
